UNITED STATES PATENT OFFICE.

CHARLES E. LARRABEE, OF OAKLAND, CALIFORNIA.

DESIGN FOR A WALL-CABINET.

SPECIFICATION forming part of Design No. 35,837, dated April 1, 1902.

Application filed April 16, 1901. Serial No. 56,132. Term of patent 7 years.

To all whom it may concern:

Be it known that I, CHARLES E. LARRABEE, a citizen of the United States, residing at Oakland, in the county of Alameda and State of California, have invented and produced a new and original Design for a Wall-Cabinet, of which the following is a specification, reference being had to the accompanying drawings, forming a part thereof.

Figure 1 is a perspective view. Fig. 2 is a front elevation, and Fig. 3 is a side elevation.

The wall-cabinet is a hollow case or box in the form of a parallelogram.

The narrow sides of the cabinet are faced with looking-glasses *b*, which extend from the top to near the bottom of the cabinet.

The front of the case or cabinet is composed of a board *e*, and in its center or near its center a looking-glass *f* is secured, which is surrounded with a suitable molding *g*. The remainder of the front surface surrounding the glass is divided off by moldings similar to *g* into various squares for containing adver-

tisements. At the bottom or lower edge of the front board a shelf or ledge *h* projects outward and below the edge, and at the back of the case the back is extended down below the box portion, and a towel-roller *2'* is mounted horizontally on the front face of the downward-projecting portion. Eyes *j* are provided in the back piece for suspending the rack against a wall. The box or case is capped and surrounded at top and bottom with an ornamental molding *l*.

It is apparent that this design is also applicable to lockers and other similar articles.

Having described my invention, what I claim as new, and desire to secure by Letters Patent, is—

The design for a wall-cabinet substantially as herein shown and described.

CHARLES E. LARRABEE.
